UNITED STATES PATENT OFFICE.

THOMAS V. FORSTER, OF HACKENSACK, NEW JERSEY.

DESIGN FOR A HOSE-RACK MEMBER.

SPECIFICATION forming part of Design No. 37,049, dated July 19, 1904.

Application filed December 11, 1902. Serial No. 134,868. Term of patent 14 years.

To all whom it may concern:

Be it known that I, THOMAS V. FORSTER, a citizen of the United States, residing at Hackensack, in the county of Bergen and State of New Jersey, have invented a new, original, and ornamental Design for a Hose-Rack Member, of which the following is a specification, reference being had to the accompanying drawing, forming part thereof.

10 The figure is an elevation showing a design of the hose-rack member.

What I claim as new, and desire to secure by Letters Patent, is—

The ornamental design for a hose-rack member, as shown.
